UNITED STATES PATENT OFFICE.

JOHN DESMOND, OF BROOKLYN, NEW YORK, ASSIGNOR TO THE HAYDEN & DERBY MANUFACTURING COMPANY, OF SAME PLACE.

STEAM-INJECTOR.

SPECIFICATION forming part of Letters Patent No. 404,262, dated May 28, 1889.

Application filed March 30, 1889. Serial No. 305,404. (Model.)

To all whom it may concern:

Be it known that I, JOHN DESMOND, a citizen of the United States of America, residing at Brooklyn, in the county of Kings and State 5 of New York, have invented certain new and useful Improvements in Steam-Injectors, of which the following is a specification, reference being had therein to the accompanying drawings.

10 This invention pertains to certain new and useful improvements in steam-injectors, having for its object, first, the production of an automatic injector comprising an overflow-chamber between the suction and combining 15 tubes and a sliding valve for presenting a continuous opening or communication between the mouth of the combining-tube and the overflow-chamber during the working of the injector, and, secondly, the provision of 20 means for regulating and controlling the supply of water to the injector, whereby the water-supply is not affected by any jarring to which the injector might be subjected.

25 In automatic injectors as heretofore constructed when the opening into the secondary overflow is once closed it so remains throughout the entire working of the injector. Better results could be obtained if the communication between the combining-tube and the overflow-chamber were uninterrupted and made 30 continuous during the working of the injector. This desirable result I have attained, and to that end the invention comprises the details of construction, combination, and arrangement of parts, substantially as hereinafter 35 fully set forth.

40 In the accompanying drawings, Figure 1 is a vertical longitudinal sectional view of my improved injector. Fig. 2 is a cross-sectional view thereof on the line $x-x$. Fig. 3 is an enlarged detail perspective view showing the sliding valve.

45 Referring to the drawings, A designates the casting or tubular casing provided with the steam-inlet arm a , the water-inlet arm a' , the overflow arm or branch a^2 , and the delivery arm or extension-nozzle a^3 , to each of which is connected the respective pipe-connection. (Not shown.) The steam-inlet arm a is ex-

tended into a chamber, B, over one end of 50 the casing, and into a circular extension, b , of the outer wall thereof is screwed a plug, b' , through the center of which is passed the stem b^2 of the steam-inlet valve C. To the outer end of this stem is loosely connected 55 the vertical arm of a lever, D, the inner end of the right-angular portion of which is fulcrumed to an ear, d , of a ring or collar, d' , disposed around the circular extension b . This ring or collar is firmly clamped or held 60 in place by the circular flange d^2 of the plug b' . By loosening said plug said ring or collar can be turned and rigidly held at the desired point so as to keep the lever-handle 65 perpendicular in case the injector is inclined toward one side. Into a circular extension, e , of the water-inlet arm a' is screwed a plug, E, through which and a second smaller plug is passed the spindle e' of a water-inlet valve, F, located in the arm a' . 70

The valve F consists of two circular heads or disks, $f-f$, centrally threaded and fitted, respectively, on the right and left hand screw-threads, $f'-f^2$, of the spindle e' . These heads or disks $f-f$ are also fitted on or guided by a rod, 75 f^3 , projecting from the plug E and extended through upper coincident apertures of said heads or disks. These heads or disks fit flush against the walls of the arm a' , and their outer ends extend into the opposite protruding circular portions of the sides of said arm. By turning the spindle e' it is obvious that the heads or disks comprising the valve will move away from or toward each other, according as they are being opened or closed. The 80 water is thus permitted to flow to or is cut off from the injector, and no matter how great the jarring (especially when the injector is used on locomotives) these heads or disks will 85 retain their same position. 90

To the spindle e' is secured a finger or pointer, f^4 , which travels over a scale, f^5 , on the flange f^6 of the plug E. This finger or pointer indicates the amount of water being forced into the boiler—*i. e.*, the quantity for 95 the passage of which the valve is adjusted.

The steam-inlet tube G projects to within a short distance of the lifting-tube H, which

latter tube is provided with an inner widened end, and is screwed into a wall, *g*, of the casting.

To the widened end of the combining-tube 5 *H'* is secured one end of the delivery-tube *I*, the latter being held in place by the arm or extension-nozzle *a*³. In the circular flange *h* of the combining-tube at the point of conjunction with the delivery-tube is formed a 10 series of holes or openings, *h'*, through which the spill or overflow passes into the overflow-chamber *h²*, wherein is formed an apertured wall, *h³*, as shown.

J is a sliding valve designed to slide on the 15 combining-tube *H'*. This valve has in one face a conical recess or opening, *j*, and a series of small grooves or recesses, *j'*, extending over the conical recess. This valve is designed to fit flush against the lifting-tube 20 during the working of the injector, and against the circular flange *h*, covering the overflow-holes *h'* in the starting thereof and until a vacuum is formed, drawing it back to its normal position, after which a passage-way be- 25 tween the mouth of the combining-tube and the overflow-chamber is had through the grooves or recesses *j'*, whereby the overflow from the holes *h'* of the combining-tube is drawn in through the said grooves or recesses, 30 thereby establishing a continuous connection between the mouth of the combining-tube and the overflow-chamber and prevent such overflow from passing out through the overflow-valve.

35 An overflow-valve, *K*, rests upon the opening between the overflow-chamber *h²* and the arm or branch, and above it is located a lazy-cock, *k*.

The operation is as follows: The steam 40 upon being admitted to the injector will pass through the steam-inlet and lifting-tubes, forcing the sliding valve *J* away from its position against said latter tube and driving the same against the circular flange *h*, and 45 said steam passing out through the holes or ports *h'* will raise the overflow-valve *K* and pass into the outside atmosphere, immediately upon which a vacuum is formed in the water-supply chamber, causing the lifting of 50 water thereinto and drawing the valve *J* back to its position against the lifting-tube. The sliding valve in thus passing through the apertured wall *h³* will stop or cut off the circulation of the overflow in the overflow- 55 chamber, which momentary cessation or stoppage will effect the establishment of the jet or column, the vacuum drawing the water in the overflow-chamber through the grooves or recesses of the sliding valve on into and 60 through the tubes to the boiler. Simultaneous with the drawing of the valve *J* to its normal position against the lifting-tube the overflow-valve is firmly closed and seals the air-inlet. The valve *J* being returned to its 65 normal position when the column of steam and water is established, a continuous passage-way between the mouth of the combin-

ing-tube and the overflow is had through the grooves or recesses *j'*, whereby any overflow through the holes *h'* is drawn in at the 70 mouth of the combining-tube, thus enabling water of a greater degree of heat to be used than is capable by any injector as heretofore constructed.

In a steam-injector provided with a secondary overflow as heretofore constructed such overflow has been kept tightly closed during the working of the injector; but practical use has demonstrated that far better results are attained by preserving a continuous 80 passage-way or communication between the combining-tube and the overflow-chamber.

I claim as my invention—

1. The herein - described improved automatic steam - injector having a continuous 85 communication between the mouth of the combining-tube and the overflow-chamber, said communication being less during the working of the injector than in the starting thereof, substantially as set forth. 90

2. A steam-injector having an overflow-chamber and the lifting and combining tubes opening thereinto, and having a continuous 95 passage-way or communication therewith, said communication being less during the working of the injector than in the starting thereof, as set forth.

3. As an improvement in steam-injectors having the lifting and combining tubes, the grooved valve sliding on said combining-tube, 100 whereby a continuous passage-way or communication is had between the mouth of said combining-tube and the overflow-chamber, as stated.

4. As an improvement in steam-injectors 105 having an overflow-chamber and the lifting and combining tubes opening thereinto, the sliding valve located at said opening of the tubes, and having holes or ports forming a continuous passage-way, substantially as set 110 forth.

5. As an improvement in steam-injectors having the overflow-chamber, the combining-tube having holes or ports at or near its rear 115 end, the sliding valve located on said combining-tube for closing said holes or ports in the starting of the injector, and having grooves or recesses for forming a continuous passage-way between the mouth of said combining-tube and the overflow-chamber, substantially 120 as set forth.

6. The herein - described improvement in steam-injectors, comprising the lifting and combining tubes, and the valve sliding on said combining-tube and having its normal 125 position against said lifting-tube, as set forth.

7. As an improvement in steam-injectors having a water-inlet arm, the water-inlet valve located in said arm and having two heads or disks fitted on dissimilar screws, and the spindle carrying a finger or pointer, substantially 130 as set forth, said heads or disks being movable in opposite directions, as stated.

8. As an improvement in steam-injectors,

the water-inlet valve having the two heads or disks, and the spindle provided with right and left hand screw-threads upon which said heads or disks are disposed, substantially as set forth.

9. As an improvement in steam-injectors, the water-inlet valve having the two heads or disks, the spindle provided with opposite screw-threads, the plug through which said spindle is passed, and the guide-rod projecting from said plug through said heads or disks, substantially as set forth.

10. In a steam-injector, the combination, with the water-inlet arm, of the valve having oppositely-movable heads or disks, the plug, the graduated scale, and the spindle having a finger or pointer, substantially as set forth.

11. In a steam-injector, the combination, with the water-inlet arm having the opposite circular extensions, of the plug having a flange provided with a scale, the heads or disks, the spindle having right and left hand screw-threads, the guide-rod projecting from said plug, and the finger or pointer, substantially as set forth.

In testimony whereof I affix my signature in presence of two witnesses.

JOHN DESMOND.
